UNITED STATES PATENT OFFICE.

GEORGE N. MORROW, OF DE BEQUE, COLORADO.

TONGS.

1,218,297.

Specification of Letters Patent.

Patented Mar. 6, 1917.

Application filed June 13, 1916. Serial No. 103,550.

To all whom it may concern:

Be it known that I, GEORGE N. MORROW, a citizen of the United States, residing at De Beque, in the county of Mesa and State 5 of Colorado, have invented certain new and useful Improvements in Tongs; and I do hereby declare the following to be a full, clear, and exact description of the invention, such as will enable others skilled in the 10 art to which it appertains to make and use the same.

My invention relates to new and useful improvements in tongs and more particularly to that class adapted to be used for 15 handling ice, skidding logs, and the like, and my object is to provide a pair of jaws which are pivotally secured together at one end and have prongs at their opposite ends for engagement with objects.

20 A further object is to provide a suitable handle which is pivotally attached to the pivoted ends of the jaws.

A further object is to provide means on 25 the handle for opening or closing the jaws.

And a further object is to provide means for normally holding the jaws in closed position.

Other objects and advantages will be 30 hereinafter set forth and more particularly pointed out in the accompanying specification.

In the accompanying drawings which are made a part of this application,

Figure 1 is an elevation of the tongs, such 35 as are used for handling ice, showing means thereon for locking the jaws in closed position.

Fig. 2 is an edge elevation of the tongs, showing the locking means in unlocked position.

Fig. 3 is a detail sectional view through the handle, showing the lock in locked position.

Fig. 4 is a similar view, showing the lock 45 in unlocked position.

Fig. 5 is a detail elevation of the upper end of a modified form of handle, and

Fig. 6 is a similar view showing the form 50 of handle employed when the tongs are used for logging purposes.

Referring to the drawings in which similar reference numerals designate corresponding parts throughout the several views; 1 indicates a handle, to the lower end of 55 which is pivotally secured a pair of jaws 2, the opposite ends of said jaws having in-

wardly and upwardly extending prongs 3 which are preferably pointed so as to readily enter into engagement with an object positioned between the jaws.

The upper end of the handle 1 is provided with a cross head 4, having a depending collar 5, into which the outer end of the handle 1 extends, the ends of the cross bar having links 6 attached thereto which is connected by a strap, or similar flexible device 7, said strap forming a hand hold for carrying the tongs.

In order to readily open or close the jaws 2, a sleeve 8 is slidably mounted on the 70 handle 1, the lower end of the sleeve having outwardly and downwardly curved arms 9 in the ends of which are formed slots 10, through which the jaws 2 extend and by means of which the jaws are swung to open 75 or closed position.

In order to readily manipulate the sleeve and arms carried thereby, a T-head 11 is attached to the outer end of the sleeve 8 so that by introducing the hand over the cross 80 head 4 and directing outward pressure against the under face of the T-head, the sleeve 8 may be easily moved longitudinally of the handle and the jaws thrown to an open position, while by directing pressure 85 in the opposite direction on the T-head, the jaws will be swung to a closed position. When the tongs are to be used for storing ice in an ice house or other building, the collar 5 and strap 7 are dispensed with, and 90 an eye 12 formed at the outer end of the handle 1 and also a cross head 13, the eye 12 being employed for attaching a rope to the handle, while the cross head 13 is provided for manually handling the tongs.

In Fig. 6 of the drawing that form of handle is shown as when the tongs are used for skidding logs, in which instance an eye 14 is formed at the outer end of the handle, while the cross head 13 is dispensed with. 100 When the tongs are used for skidding logs or for similar purposes the chain or cable attached to the eye 14 frequently becomes slack, and in order to hold the tongs securely clamped in engagement with the log 105 until such time as it is desired to release the same, a ring 15 is disposed around the handle, between the T-head 11 and the collar 5, the opening 16 in the ring being of a greater diameter than the diameter of the 110 handle, so that the ring will freely slide upon the handle but will frictionally engage

2
and interlock with the handle when the ring is tilted or disposed at an angle to the axis of the handle, and in order to hold the ring canted, an L-shaped dog 17 is attached to the ring 15, the angular extension of the dog resting upon the face of the T-head 11 when the ring is employed for locking the jaws against opening movement. When the tongs are used for carrying ice, or for similar purposes, the ring is rotated on the handle until the dog extends at right angles to the T-head 11, thereby permitting the ring to assume its natural position around the handle whereby the sleeve may be readily moved lengthwise of the handle to open or close the jaws without interference from the ring.

If preferred, that portion of the ring 15, opposite the dog 17, may be provided with a curved lip 18 which may be readily grasped to move the ring to a level position to unlock the same from the handle, or, if preferred, the lip may be dispensed with and a blow delivered to the dog 17 to move the same laterally out of engagement with the T-head, and the ring structure may be entirely dispensed with when the tongs are to be used for household purposes, such as carrying small cakes of ice, and the like.

In applying the tongs to use when used for household purposes, the hand is placed over the cross bar and the fingers inserted below the T-head 11 when the fingers are closed, thus moving the sleeve 8 lengthwise of the handle and swinging the jaws open. The jaws are then positioned on opposite sides of the object to be carried and the pressure released from the T-head, when the jaws, under ordinary circumstances, will close by their own weight and the weight of the sleeve and dispose the prongs 3 into engagement with the object. Should the jaws refuse to close by their own weight, however, a pressure may be directed against the T-head, thus forcing the jaws to closed position, and as soon as the prongs have engaged the object and an upward lifting motion given the tongs, the prongs will be forced into the object and caused to firmly grip the same.

When the prongs are used for logging purposes, such as skidding logs through growing timber, or in moving the same from place to place, after the jaws have been moved inwardly until the prongs are embedded within the log, the ring 15 is swung on the handle until the dog 17 is in registration with one arm of the T-head 11 when a downward pressure is directed against that edge of the ring having the lip 18, thereby disposing the ring at an angle to the axis of the handle and causing the edges of the ring to impinge against the exterior

of the handle on opposite sides, thereby securely locking the sleeve against outward movement so that, even though the pull on the end of the handle is slackened, the tongs are not released from the log until the ring is lifted or the dog disengaged from the T-head.

I claim:—

1. The herein described tong comprising a handle, a pair of jaws pivoted to one end of the handle, prongs on said jaws, a sleeve slidably mounted on the handle, a T-head at one end of the sleeve, a pair of curved arms at the opposite end of the sleeve having slots therethrough through which the jaws extend, and means to lock the sleeve against outward movement on the handle.

2. The herein described tongs comprising a handle, a pair of jaws pivotally attached to one end of the handle, prongs on said jaws, a sleeve slidably mounted on the handle, curved arms carried by the sleeve having slots adjacent their free ends through which the jaws extend, a T-head at the end of the sleeve opposite the arms, a ring surrounding the handle between the T-head and outer end of the handle, said ring having an opening greater in diameter than the diameter of the handle, and means to tilt the ring at an angle to the trend of the handle whereby said ring will frictionally engage the handle and prevent outward movement of the sleeve.

3. A tong of the class described, comprising the combination with a handle and a pair of jaws pivotally secured to said handle, of a sleeve slidably mounted on the handle, curved arms at one end of said sleeve, said arms having slots through which said jaws extend, and a T-head at the opposite end of the sleeve adapted to receive pressure whereby said jaws may be swung to open or closed position by the movement of the sleeve on the handle.

4. The herein described tong comprising the combination with a handle and a pair of jaws pivotally secured to one end of the handle, of a sleeve slidably on said handle, arms at one end of the handle having slots therethrough for the reception of said jaws, a T-head at the opposite end of said sleeve, a ring surrounding said handle, and an L-shaped dog carried by the ring adapted to tilt the ring to cause the edges thereof to grip the handle and prevent outward movement of the sleeve.

In testimony whereof I have signed my name to this specification in the presence of two subscribing witnesses.

GEORGE N. MORROW.
